UNITED STATES PATENT OFFICE.

JOHN G. DYBENS, OF LOS ANGELES, CALIFORNIA, ASSIGNOR TO HERMAN D. EBERLE,
OF LOS ANGELES, CALIFORNIA.

HYDRAULIC JACK.

Application filed March 16, 1926. Serial No. 95,041.

This invention relates to an improved form of hydraulic jack.

A common form of hydraulic jack has an inner piston cylinder in which a piston is situated and an outer reservoir cylinder which surrounds the piston cylinder and in which oil is reserved. A pump is provided for drawing oil from the reservoir chamber and forcing it into the piston chamber in order to elevate the piston, there being suitable passages and valves for permitting this. The common hydraulic jack also has a by-pass having a by-pass valve which may be opened in order to allow the liquid to flow from the piston chamber into the reservoir chamber when it is desired to lower the piston.

It is an object of this invention to provide an hydraulic jack in which the passages connecting the reservoir chamber and the piston chamber with the pump and the by-pass passage are all connected together and designed for simplicity and economy in making and assembling these parts of the jack.

It is another object of this invention to provide an hydraulic jack in which the cylinders forming the piston chamber and the reservoir chamber are assembled together in an improved and simplified manner.

In the ordinary hydraulic jack, when oil is drawn from the reservoir chamber and forced into the piston chamber, a vacuum is created in the reservoir chamber which, of course, tends to prevent the liquid from being drawn therefrom.

It is an object of this invention to provide a vacuum relief valve whereby air may be introduced into the reservoir chamber when the oil is drawn therefrom so that there will be no vacuum created.

It is another object of this invention to provide a vacuum valve of the character mentioned which is closed when the piston is in lower position so that there will be no leakage of oil therethrough from the reservoir chamber.

Referring to the drawing in which I illustrate a preferred form of my invention,

Fig. 1 is a perspective view of a jack embodying the features of this invention.

Fig. 2 is a vertical cross section taken substantially as indicated by the line 2-2 of Fig. 1.

Fig. 3 is a fragmentary section taken as indicated by the line 3-3 of Fig. 1.

Fig. 4 is an enlarged fragmentary detail of the vacuum relief valve of this invention.

Referring particularly to Figs. 1 and 2 of the drawing, my invention provides a base 11 having a central threaded cavity 12 into which the lower end of an inner cylinder 13 is secured, this inner cylinder 13 providing a piston chamber 14. The upper end of the inner cylinder 13 is screwed into a threaded cavity 15 of a cap 16. A piston 17 is placed in the piston chamber 14 and is adapted to move from a lower into an upper position. Extending from the piston 17 is a stem 18 which projects through a stuffing box 19 of the cap 16, there being a head 21 formed at the upper end of the stem 18.

Surrounding the threaded cavity 12 of the base 11 is an annular internal beveled seat 23 and surrounding the threaded cavity 15 of the cap 16 is an annular external beveled seat 24. The numeral 25 represents an outer cylinder which surrounds the inner cylinder 13 and forms an annular reservoir chamber 26; 28 represents an upper internal beveled end of the outer cylinder 25 and 29 represents a lower external beveled end of the outer cylinder 25. The beveled ends 28 and 29 are forcibly engaged respectively by the beveled seats 24 and 23 of the cap 16 for the base 11. In assembling these parts, the inner cylinder 13 may first be screwed into the threaded cavity 12 of the base 11. The outer cylinder 25 may then be set in position to surround the inner cylinder 13, whereafter the cap 16 is screwed onto the upper end of the inner cylinder 13, the upper threaded end of the cylinder 13 advancing into the threaded cavity 15 of the cap 16. The cap 16 is screwed onto the inner cylinder 13 to such an extent that the beveled faces 23 and 24 forcibly engage the beveled ends 29 and 28 of the outer cylinder 25 a sufficient amount to form tight joints between the parts 11, 16 and 25. This construction is very simple and is very easy to assemble.

The body 11 has a projection 30 which extends upwardly at one side of the outer cylinder 25, this projection 30 providing a pump cylinder 31 in which a pump plunger 32 is placed, there being a stuffing box 33 at the upper end of the cylinder 31 to form a seal therat. The upper end of the plunger 32 may be provided in the form of a clevis 35 which is attached to an operating arm 37 by a pin 36. The operating arm 37 is also

attached to a link 38, as illustrated in Fig. 1, the lower end of this link being pivoted to the base.

The reservoir chamber 26 is connected to the lower end of the pump cylinder 31 by means of a suction passage 42. The suction passage 42 is enlarged at its outer end at 43 so as to provide a seat 44. Adapted to engage the seat 44 is an intake valve in the form of a ball 45. The ball 45 is held in the left end of the enlarged part 43 by means of a pin 46 which extends from a plug 47 which is threadedly secured in the right end of the enlarged part 43. A branch 49 of the suction passage 42 connects between the enlarged part 43 and the lower end of the pump cylinder 31. The lower end of the piston chamber 14 is connected to the lower end of the pump cylinder 31 by means of an exhaust passage 51. The exhaust passage 51 is drilled from the right end of the base 11 and is enlarged at 52 so as to provide a seat 53. Extended into the enlarged part 52 is an exhaust valve unit 54 having a body 55. The outer part of the body 55 is threaded at 56 and screws into the enlarged part 52 so that the left end of the body engages the seat 53 and there is a tight seal provided thereat. The left end of the body 55 has a chamber 57 in which a ball valve 58 is placed. The ball valve is adapted to engage a seat 59 and to close an opening 60 which is communicated with the lower end of the pump cylinder 31 by means of a diametrical opening 62. A by-pass opening 64 is drilled so as to connect the suction passage 42 and the exhaust passage 51 together at a point between the reservoir chamber and the piston chamber and the pump cylinder 31. The by-pass passage is enlarged at 65 so as to provide a seat 66. Extending into the enlarged part 65 of the by-pass passage 64 is a by-pass valve 67. The upper end of the by-pass valve 67 is surrounded by a stuffing box 68. A gland 69 of the stuffing box is provided with internal threads and the valve 67 is provided with external threads 70 which screw into the internal threads of the gland 69 so that the by-pass valve 67 may be advanced in either direction. The lower part 72 of the by-pass valve 67 is of smaller size than the enlarged part 65 of the by-pass passage 64. Therefore, the extending of the lower end 72 into the portion 65 does not obstruct a flow of oil through the suction passage 42, since there is a space left there-around through which the oil may flow into the enlarged part 43 of the suction passage 42.

Considering the piston 17 to be in lower position in the piston chamber 14, it may be raised by operating the pump plunger 32, this being done by oscillating the member 37. During the up stroke of the plunger 32, the ball valve 58 in the chamber 57 is

pulled against its seat and prevents a flow from the piston chamber 14 into the lower end of the pump cylinder 31. The suction valve 45, however, is withdrawn from its seat against the end of the pin 46 and liquid is drawn from the reservoir chamber 26 into the pump cylinder 31 through the suction passage 42, it being understood that the reservoir chamber 26 is filled with a liquid which is of a viscous nature such as heavy lubricating oil. During the down stroke of the plunger 32, the suction valve 45 is forced against the seat 44 and the suction passage 42 is closed so that there cannot be a flow of oil from the pump cylinder 31 to the reservoir chamber 26. The ball 58, however, is forced from its seat 59 and the oil previously drawn into the pump cylinder 31 is forced through the exhaust passage 51 into the lower end of the piston chamber 14. As oil is forced into the piston chamber 14 the piston 17 is moved upwardly from a lowered position into a raised position, as shown in Figs. 1 and 2. When it is desired to lower the piston 17 and to lower the jack, the oil in the piston chamber must be returned to the reservoir chamber. This is accomplished by unscrewing the by-pass valve 67 so that it disengages from the seat 66. This opens the by-pass passage 64 and oil may flow from the piston chamber 14 through a part of the exhaust passage 51, the by-pass passage 64 and through a part of the suction passage 42 into the reservoir chamber 26.

From an inspection of Fig. 2, it will be obvious that as the oil is withdrawn from the reservoir chamber 26 a vacuum will be created thereabove and this vacuum will tend to resist the withdrawal of the oil from this reservoir chamber. My invention provides a vacuum relief valve 70 which is shown best in Figs. 2 and 4. The cap 16 is provided with an opening 71 which extends from the exterior to the interior of the reservoir chamber 26. A body 72 of the vacuum relief valve 70 extends through the opening 71 and has a threaded portion 73 which screws into a threaded portion of the opening 71, whereby it is secured in place. The body 72 is provided with a cavity 74 which is decreased in size at 76 so as to provide an annular seat as indicated at 77. The lower end of the cavity 74 is connected to the upper part of the reservoir chamber 26 by means of a small opening 78. A valve 79 is placed in the cavity 74 in position to engage the seat 77. Placed below a projection 81 of the valve 79, which projection extends into the small part 76 of the cavity 74, is a spring 82 which tends to keep it elevated and unseat the valve 79. In the upper part of the cavity 74 is a valve urger 83 having a stem 84, which projects through a swaged portion 85 at the upper part of the cavity 74, and has a head 85* which rests

inside the upper part of the cavity 74. Situated between the head 85^a and the valve 79 is a spring 86. Channels 88 extend from the upper end of the cavity 74 to a point 5 adjacent to the seat 77, and channels 89 extend from the seat 77 to the lower part of the small part 76 of the cavity 74. The vacuum relief valve 70 is situated in such a position that the stem 84 of the urger 83 10 rests below the head 21. When the head 21 moves into lower position, as indicated by dotted lines 90 in Fig. 1, the stem 84 is engaged and the urger 83 is pressed downwardly into the position shown in Fig. 4. A 15 pressure is transferred through the spring 86 against the valve 79, the valve 79 being forced against the seat 77 so that the cavity 74 is closed. The spring 82 below the valve 79 is of sufficient strength to keep it unseated at all times except when the head 21 20 is in engagement with the stem 84 of the urger 83. From this it will be seen that when the piston 17 is in lowered position and the jack is not in use, the valve 79 will 25 be in engagement with the seat 77 and the passage through the body 72 will be closed. When the jack is operated and oil is withdrawn from the reservoir chamber 26, the head 21 will be moved from engagement 30 with the urger 83 and the spring 82 will lift the valve 79 from its seat. This opens the passage through the body 72 and communicates the reservoir chamber 26 with the atmosphere. Therefore, whenever oil is being 35 withdrawn from the reservoir chamber 26, air may enter thereinto through the vacuum relief valve 70. Also, when oil is being returned to the reservoir chamber 26 air previously drawn thereinto through the vacuum relief valve 70 may be exhausted there-through. This valve arrangement of my 40 invention eliminates any vacuum in the reservoir chamber 26 at any time but is so designed that the valve will be closed when 45 the jack is not in use so that there cannot be any leakage in event that the jack was laid on its side so that oil would run out if the valve closing means were not provided.

50 From the foregoing description it will be evident that this invention provides a jack having three main features: first, the novel construction of passages connecting the reservoir chamber and the piston chamber with the pump cylinder 31, the valve constructions, and the by-pass construction; second, the novel means whereby the inner and outer cylinders 13 and 25 are secured in place which is very satisfactory because they are 55 economical to produce and economical to assemble; and, third, the vacuum relief valve 70 which prevents the creating of a vacuum in the reservoir chamber 26, but also prevents a leakage of oil from the chamber when the 60 jack is not in use.

I claim as my invention:

1. An hydraulic jack comprising: a base having a threaded portion and an annular beveled seat surrounding said threaded portion; an inner cylinder having the lower end 70 screwed to said threaded portion of said base; a cap having a threaded portion to which the upper end of said inner cylinder is screwed, and an annular beveled seat surrounding said threaded portion; and an 75 outer cylinder having the ends thereof beveled, said beveled ends being forcibly engaged by said annular beveled seats of said base and said cap, thus forming tight joints at the opposite ends of said outer cylinder. 80

2. An hydraulic jack comprising: walls forming a piston chamber and a reservoir chamber; a piston adapted to operate in said piston chamber; means for pumping a liquid from said reservoir chamber into said piston 85 chamber and for allowing said liquid to return to said reservoir chamber from said piston chamber; a vacuum relief valve for admitting air into said reservoir chamber when liquid is taken therefrom and emitting 90 air when said liquid is returned to said reservoir chamber; and means carried by said piston for closing said vacuum valve when said piston is approximately in lower position. 95

3. An hydraulic jack comprising: walls forming a piston chamber and a reservoir chamber; a piston adapted to operate in said piston chamber; means for pumping a liquid from said reservoir chamber into said piston 100 chamber and for allowing said liquid to return to said reservoir chamber from said piston chamber; a vacuum relief valve for admitting air into said reservoir chamber when liquid is taken therefrom and emitting 105 air when said liquid is returned to said reservoir chamber; and means for closing said vacuum valve when said piston is approximately in lower position.

4. An hydraulic jack comprising: walls 110 forming a piston chamber and a reservoir chamber; a piston adapted to operate in said piston chamber; a base attached to said walls forming said piston and reservoir chambers, said base having a pump cylinder, an exhaust passage connected to said piston chamber and said pump cylinder, a suction passage connected to said reservoir chamber and said pump cylinder, and a by-pass connected to said exhaust and said suction passages 115 between said piston and said reservoir chambers and said pump cylinder; a suction valve in said suction passage for preventing a flow of liquid from said pump cylinder to said reservoir chamber; an exhaust valve in said 120 exhaust passage for preventing a flow of liquid from said piston chamber to said pump cylinder; a pump plunger operable in said pump cylinder for drawing liquid from said reservoir chamber through said suction 125 passage. 130

passage and delivering said liquid to said piston chamber through said exhaust valve; a by-pass valve for closing said by-pass, said by-pass valve being manually operable to permit said liquid to return through said exhaust passage, said by-pass and said suction passage from said piston chamber to said reservoir chamber; a vacuum relief valve for admitting air into said reservoir chamber when liquid is taken therefrom and emitting air when said liquid is returned to said reservoir chamber; and means carried by said piston for closing said vacuum valve when said piston is approximately in lower position.

In testimony whereof, I have hereunto set my hand at Los Angeles, California, this 11th day of March, 1926.

JOHN G. DYBENS.
